DRAFT AND BUFFER GEAR

Roland J. Olander, Chicago, Ill., assignor to W. H. Miner, Inc., Chicago, Ill., a corporation of Delaware

Application October 17, 1934, Serial No. 748,699

16 Claims. (Cl. 213—9)

This invention relates to improvements in draft and buffer gears especially adapted for use in connection with mine cars.

One object of the invention is to provide a combined draft and buffer gear for cars of simple and rugged design, wherein both the draft and buffering shocks are cushioned by the same shock absorbing means.

Another object of the invention is to provide in a gear of the character indicated, including shock absorbing means, mechanism for compressing the shock absorbing means inwardly toward the end of the car in both buff and draft, wherein said mechanism comprises a pair of buffering heads and a draft member cooperating with the buffering heads for forcing the latter inwardly in draft to compress the shock absorbing means, the draft member being so arranged and designed as to effectively resist bending strains during draft action of the mechanism.

A more specific object of the invention is to provide a combined draft and buffer gear for mine cars, including cushioned buffer heads at opposite sides of the end of the car, and draft means centrally of the end of the car in the form of a single rocking lever member having camming action on the buffer heads to force the latter inwardly against the cushioning means.

A still further object of the invention is to provide a draft member in a mechanism of the character specified in the preceding paragraph, which is rockable about a horizontal axis, and has a pair of arms which have camming engagement respectively with the buffering heads, wherein the arms are formed integral with a connecting barlike portion adapted to extend through a link member, forming a part of the coupling means, to operatively couple the draft member to an adjacent car.

Yet another object of the invention is to provide a combined draft and buffer gear of the character set forth, so designed that the same may be quickly and easily assembled and held in said assembled relation by novel retaining means so arranged as to be free of all strains due to the operation of the gear.

Other objects of the invention will more clearly appear from the description and claims hereinafter following.

In the drawing forming a part of this specification, Figure 1 is a horizontal sectional view, partly broken away, of one end of a mine car, illustrating my improvements in connection therewith, the section corresponding substantially to the line 1—1 of Figure 2. Figure 2 is a

front elevational view of the structure shown in Figure 1. Figure 3 is a vertical sectional view, corresponding substantially to the line 3—3 of Figure 2.

In said drawing, 10 designates the end portion of a mine car to which my improved combined draft and buffer gear is attached. My improvements comprise broadly a support A secured to the car; a pair of buffering heads B—B; a draft member C; and two sets of springs D—D 10 and D—D. As shown, the mine car is provided with the usual end sill 11, bottom wall 12, and end wall 13. The end wall is reinforced by an angle bar 14 and the bottom wall 12 is secured to the end sill, as shown.

The support A comprises a plate section 15, inturned, vertically extending, side flanges 16—16, and an inwardly extending, horizontal bottom flange 17. The support A is fixed to the end of the car by means of rivets, or any other similar securing elements, extending through the plate section 15 and the vertical end wall 10 of the car, the side flanges 16—16 and the side walls 12—12 of the car, and through the bottom flange 17 and the bottom wall 12 of said car. At opposite sides of the car, the support A is provided with horizontally extending, vertically spaced, top and bottom webs 18—18 and 18—18. Adjacent to the outer ends, the top and bottom webs 18—18 at each side of the car are provided with outstanding ear portions 19—19, which have vertically aligned bolt-receiving openings. The top and bottom webs 18—18 of each set are provided with vertically disposed, transverse flanges 20—20 at their outer edges, the flange 20 of the upper web projecting downwardly and the flange 20 of the lower web projecting upwardly. The flanges 20—20 of each set of webs 18—18 are cut away at their outer ends adjacent to the ears 19—19, as indicated at 21—21. At the inner 40 ends, the top and bottom webs 18—18 of each set are provided with transversely extending stop flanges 22—22, the stop flange 22 of the upper web being directed downwardly and the stop flange of the lower web being directed upwardly. 45

The buffering heads B—B, which are disposed at opposite sides of the end of the car, are of like design. Each buffering head is in the form of a hollow cuplike member having a vertically disposed front wall 23, spaced, horizontally disposed, top and bottom walls 24—24, and spaced, vertical, side walls 25—25. The front wall 23 presents an outer buffering face, which cooperates with the outer buffering face of a similar buffering head B on an adjacent car. The top and bot-

tom walls 24-24 of each buffing head are provided with transverse, vertical flanges 26-26 at their inner ends. The side walls 25-25 of each buffing head are provided with vertically disposed flanges 27-27 at their inner ends. As most clearly shown in Figure 2, the inner ends of the flanges 26-26 and the upper and lower ends of the inner flange 27 of each buffing head are cut away or notched, as indicated at 28. The top and bottom flanges 26-26 of the buffing heads B-B are engaged in back of the flanges 20-20 and 20-20 of the webs 18-18 and 18-18 of the support A. The shoulders on the top and bottom flanges 26-26 of each buffing head, which shoulders are formed by the cut away portions 28-28, have shouldered engagement with the transverse flanges 22-22 at the corresponding side of the support A, thereby limiting lateral inward displacement of the buffing head. Each buffing head is also held against lateral outward movement by a retaining bolt 29 extending through the openings of the ears 19-19 at the corresponding side of the support A. As most clearly shown in Figures 1 and 2, each bolt 29 is disposed in front of the vertical flange 27 at the outer side of the corresponding buffing head B and engages the outer side wall 25 of said head.

The draft member C comprises a pair of spaced, vertical arms 30-30 connected at their upper ends by a transverse rodlike portion 31, which is preferably of cylindrical cross-section. The rodlike portion 31 is of such a size as to pass freely through a link 32 which forms part of the means for coupling the car to another car. At the lower ends of the arms 30-30, the draft member C is provided with laterally extending bearing portions 33-33, which are of cylindrical cross-section. At the outer ends, the bearing portions 33-33 are provided with cam lugs 34-34, which bear on the inner flanges 27-27 of the buffing heads B-B. The draft member C is swingingly supported on the support A by means of U-shaped bearing brackets 35-35, which are fixed to the vertical plate section 15 of the support A by means of rivets, or other similar securing elements extending through securing lugs 36-36 and 36-36 of said U-shaped bearing brackets and said plate section 15. The loops of the U-shaped bearing brackets 35-35 are of such a size, as clearly shown in Figure 3, as to form bearing means for rotatably supporting the bearing portions 33-33 of the draft member C.

The springs D-D and D-D, which yieldingly oppose inward movement of the buffing heads B-B, are arranged in pairs at opposite sides of the mechanism, each pair being contained within the corresponding buffing head B and the spring members D-D of said pair having their front and rear ends bearing respectively on the inner side 60 of the front wall 23 of the buffing head and on the front face of the plate section 15 of the support A.

In assembling the parts of the mechanism, the flanges 26-26 and 26-26 of the buffing heads are engaged in back of the flanges 20-20 and 65 20-20 of the support A by sliding the buffing heads B-B with the springs D-D therein, laterally inwardly. After the parts have been thus far assembled, the bolts 29-29 are attached to the ears 19-19 and 19-19, thereby holding the 70 buffing heads against lateral displacement. As will be evident, by arranging the bolts 29-29, as described, the same serve merely to hold the parts in position by preventing lateral movement of the buffing heads B-B, said bolts not being 75 placed under any strain during the action of the

gear, the flanges 26-26 and 26-26 of the support A being the sole means for limiting outward movement of the buffing heads. The coupling link 32 is assembled with the draft member C by engaging the link over one of the cam lugs 34 of said draft member and then passing the link over the bearing portion 33, the arm 30, and the connecting portion 31. The draft member is next secured in position by means of the U-shaped supporting brackets 35-35 with the cam lugs 34-34 bearing on the inner flanges 27-27 of the buffing heads B-B.

The operation of my improved draft and buffing gear is as follows: Upon a pulling force being applied to the link 32, the draft member A will 15 be swung outwardly, pivoting on the bearing portions 33-33, thereby swinging the cam lugs 34-34 inwardly against the inner flanges 27-27 of the two buffing heads, and rocking the heads inwardly against the springs D-D and D-D. 20 During the buffing action, the heads B-B are forced inwardly against the cushioning springs D-D and D-D. Outward movement of the buffing heads B-B is limited by the flanges 26-26 and 26-26 thereof coming into engagement with 25 the flanges 20-20 and 20-20 of the support A.

I have herein shown and described what I now consider the preferred manner of carrying out my invention, but the same is merely illustrative and I contemplate all changes and modifications that 30 come within the scope of the claims appended hereto.

I claim:

1. In a combined draft and buffer gear for cars, the combination with fixed abutment means on 35 the end of the car; of a supporting member; buffing heads at opposite sides of said end of the car, said heads being slidable inwardly on the supporting member; cushioning means interposed between each head and the abutment 40 means and opposing inward movement of said head; and a draft member comprising vertically disposed lever means swingable about a fixed horizontal pivotal axis on said supporting member, said lever means engaging both of said 45 buffing heads for forcing said heads inwardly toward said fixed abutment means.

2. In a combined draft and buffer gear for cars, the combination with fixed abutment means on the end of the car; of a supporting member; 50 buffing heads at opposite sides of said end of the car, said heads being slidable inwardly on the supporting member; cushioning means interposed between each head and the abutment means and opposing inward movement of said 55 head; and a rocking draft member mounted on said support between said buffing heads, said draft member having a pair of lever arms rigid therewith and in camming engagement, respectively, with buffing heads to force said heads inwardly toward said fixed abutment means.

3. In a combined draft and buffer gear for cars, the combination with fixed abutment means on the end of the car; of a supporting member; buffing heads at opposite sides of said end of the 65 car, said heads being slidable inwardly on the supporting member; cushioning means interposed between each head and the abutment means and opposing inward movement of said head; and a vertically disposed rocking draft 70 member between said buffing heads, said draft member being pivoted on said support for swinging movement about a horizontal axis, said draft member having means rigid therewith at one side of the pivotal axis thereof for attachment of 75

- a coupling element and having means rigid therewith at the opposite side of said pivotal axis engaging the buffing heads for forcing the latter inwardly toward said fixed abutment means.
5. 4. In a combined draft and buffer gear for cars, the combination with fixed abutment means on the end of the car; of a supporting member; buffing heads at opposite sides of said end of the car, said heads being slidable inwardly on the 10 supporting member; cushioning means interposed between each head and the abutment means and opposing inward movement of said head; a vertically disposed rocking draft member between said buffing heads, said draft member being pivoted on said support for swinging movement about a horizontal axis; a coupling element connected to said draft member above said axis; and means on said draft member below said axis having camming engagement with 15 the buffing heads for forcing the latter inwardly toward said fixed abutment means.
5. In a combined draft and buffer gear for cars, the combination with fixed abutment means on the end of the car; of a supporting member; 20 buffing heads at opposite sides of said end of the car, said heads being slidable inwardly on the supporting member; cushioning means interposed between each head and the abutment means and opposing inward movement of said head; a vertically disposed rocking draft member between said buffing heads, said draft member being pivoted on said support for swinging movement about a horizontal axis; a coupling element connected to said draft member above 25 said axis; and a pair of laterally spaced depending arms on said draft member having camming engagement respectively with said buffing heads to force the latter inwardly toward said fixed abutment means.
40. 6. In a combined draft and buffer gear for cars, the combination with fixed abutment means on the end of the car; of a supporting member; buffing heads at opposite sides of said end of the car, said heads being slidable inwardly on the supporting member; cushioning means interposed between each head and the abutment means and opposing inward movement of said head; and a draft member disposed between said buffing heads, said draft member comprising a 45 pair of vertically disposed spaced arms, pivoted between their ends to swing about a horizontal axis, and a transversely disposed coupling link receiving member rigidly connecting the upper ends of said arms, the lower ends of said arms having camming engagement with said buffing heads to force the latter inwardly toward said fixed abutment member.
60. 7. In a combined draft and buffer gear for cars, the combination with fixed abutment means on the end of the car; of a supporting member; buffing heads at opposite sides of said end of the car, said heads being slidable inwardly on the supporting member; cushioning means interposed between each head and the abutment means and opposing inward movement of said head; and a draft member disposed between said buffing heads, said draft member comprising a pair of vertically disposed spaced arm members rigidly connected at their upper ends by a transverse bar element adapted to extend through a coupling link, a pair of laterally extending bearing portions on the lower ends of said arm members journaled on said support for rotation about a horizontal axis, and arm members projecting radially from said bearing portions and

engaging said buffing heads to force the latter inwardly toward said fixed abutment member.

8. In a combined draft and buffer gear for cars, the combination with a supporting member on the end of the car; of spaced buffing heads 5 slidable inwardly on said supporting member, said heads having bearing surfaces at adjacent ends; means on said member limiting outward movement of the buffing heads; cushioning means yieldingly opposing inward movement of said 10 heads; and a draft member comprising a draft arm and vertically disposed lever means fixed to said arm and swingable about a horizontal pivotal axis on said supporting member, said lever means engaging with the bearing surfaces of 15 said heads to force said heads inwardly toward the end of the car.

9. In a combined draft and buffer gear for cars, the combination with a supporting member on the end of the car; of laterally spaced buffing 20 heads slidable inwardly in a horizontal direction on said supporting member; laterally projecting flanges on the inner sides of the buffing heads; means yieldingly opposing movement of said 25 heads inwardly toward the end of the car; means on said supporting member, limiting outward movement of said buffing heads; a swinging draft member; means on said support for supporting said draft member for swinging movement, about a horizontal axis, between said heads; and means on said swinging member, rigid therewith, engaging said flanges of the buffing heads for forcing said heads inwardly toward said end of the car when said swinging member is actuated in draft. 30

10. In a combined draft and buffer gear for cars, the combination with a supporting member having horizontally disposed top and bottom walls provided with transverse abutment flanges at their outer ends; of laterally spaced buffing heads 40 slidable inwardly between said top and bottom walls, said heads having transverse top and bottom stop flanges engageable with said flanges of the supporting member to limit outward movement of said heads, each of said heads also having a laterally projecting vertical flange at the inner side thereof; means yieldingly opposing movement of said heads inwardly toward the end of the car; and a draft member comprising vertically disposed lever means forming fixed parts 45 of said draft member and swingable about a horizontal axis on said supporting member, said lever means having engagement with the inner flanges of the buffing heads for forcing said heads inwardly toward said end of the car. 50

11. In a combined draft and buffer gear for cars, the combination with a supporting member at the end of the car, said supporting member having horizontally disposed top and bottom walls at opposite sides of said end of the car, 60 said top and bottom walls having vertically disposed, transversely extending, abutment flanges at their outer ends; of inner stop shoulders on said top and bottom walls at each side of said end of the car; laterally spaced buffing heads slidable 65 inwardly between said top and bottom walls, said heads having transverse top and bottom stop flanges engageable with said flanges of the supporting member to limit outward movement of said heads, said heads also having laterally projecting, vertically disposed, flanges at the inner and outer sides thereof, each of said heads being held against lateral inward displacement by the stop shoulders at the corresponding side of said 70 end of the car; detachable retaining means ex- 75

tending through the top and bottom walls of said supporting member engaging the lateral outer sides of said heads to hold said heads against lateral outward displacement; means yieldingly opposing movement of said heads inwardly toward said end of the car; and a draft member comprising vertically disposed lever means swingable about a horizontal axis on said supporting member, said lever means having engagement with the flanges at the inner sides of said heads for forcing the latter inwardly toward said end of the car.

12. In a combined draft and buffer gear for cars, the combination with a supporting member; of laterally spaced buffing heads movable inwardly on said supporting member; means yieldingly opposing inward movement of the buffing heads; and a crank member journaled on said support for actuating the buffing heads, said crank member having an arm engageable with a coupling link.

13. In a combined draft and buffing gear for cars, the combination with a supporting member; of a buffing head movable inwardly with respect to said supporting member; means yieldingly opposing inward movement of said head; and a crank member for actuating said buffing head, said crank member including a bearing portion journaled on said support, and radial arms at opposite sides of said bearing portion, one of said arms having bearing engagement with the buffing head and the other of said arms receiving the pulling force in draft.

14. In a combined draft and buffing gear for cars, the combination with a supporting member, of laterally spaced buffing heads movable inwardly with respect to said supporting member; means

yieldingly opposing inward movement of said heads; a crank member journaled on said supporting member for actuating said heads, said crank member having an offset central crank portion adapted to receive the pulling forces in draft. 5

15. In a combined draft and buffing gear for cars, the combination with a supporting member; of laterally spaced buffing heads movable inwardly with respect to said supporting member; means yieldingly opposing inward movement of said heads; a crank shaft member between said heads, said crank shaft member having spaced bearing portions journaled on said support for mounting said shaft for rotation about a horizontal axis, 10 said shaft having an offset crank portion between said bearing portions receiving the pulling force in draft; and means on said shaft engaging the buffing heads to actuate the same when the shaft is rotated. 15

16. In a combined draft and buffing gear for cars, the combination with a supporting member; of a crank shaft having an offset crank portion between the ends thereof, said shaft being journaled at opposite ends on said member for rotation about a horizontal axis, said offset crank portion receiving the pulling force in draft; a pair of buffing heads at opposite ends of the crank shaft, said heads being movable inwardly with respect to said supporting member; means yieldingly opposing inward movement of said heads; and means on said crank shaft having camming engagement with the buffing heads for forcing the same inwardly. 20 25 30
